ATTACHE CASE

Roy L. Lawson, 2085 Sutter St.,
San Francisco, Calif. 94115

Continuation-in-part of design application Ser. No. 5,561,
Jan. 25 1967. This application Oct. 4, 1967, Ser. No.
8,865

Term of patent 14 years

(Cl. 87—5)

FIG. 1.

FIG. 2.

FIG
3.FIG
4.FIG
5.FIG
6.

This is a continuation-in-part of design application Ser. No. D. 5,561, filed Jan. 25, 1967, now abandoned.

I claim.

The ornamental design for an attaché case, substantially as shown and described.
